INVERTED SIPHON DRAIN FOR TANK ROOFS

John H. Wiggins, Chicago, Ill.

Application February 15, 1943, Serial No. 475,927

5 Claims. (Cl. 182—7)

This invention relates to drains for removing water from the roofs or tops of gas and/or liquid storage tanks, and particularly inverted siphon drains for floating roofs and breather type roofs of the kind now used extensively on tanks in which gases, gasoline and crude oil are stored.

One objectionable feature or characteristic of the conventional tank roof inverted siphon drain is that it cannot be cleaned, inspected, or repaired while the tank is in normal operation, due to the fact that parts of the drain which are located on the underside of the roof are not accessible until after a screw-threaded joint has been disconnected so as to enable the parts of the drain to be drawn upwardly through an opening in the roof.

The main object of my invention is to provide an inverted siphon roof drain of novel construction whose parts are accessible from the top side of the roof for inspection, cleaning, or replacement, when the tank is in normal operation, i. e., in the case of a floating roof when the roof is supported by or floating on the liquid in the tank, and in the case of a breather type roof, when the tank is under pressure.

Another object is to provide a tank roof inverted siphon drain, in which water may safely be used to constitute the liquid sealing medium of the drain, due to the fact that the drain is of such construction or design that at freezing temperatures the sealing water can freeze solid, without breaking or cracking the parts of the drain, and when the temperature moderates, said water will melt and again function as a liquid sealing medium for the drain.

And still another object of my invention is to provide a tank roof inverted drain that is equipped with a removable sealing member or baffle, and means whereby the operation of removing said sealing member automatically closes the discharge pipe or outlet of the drain, and the operation of restoring said sealing member automatically opens said discharge pipe or outlet. Other objects and desirable features of my invention will be hereinafter pointed out.

Figure 1 of the drawing is a fragmentary top plan view of a floating tank roof equipped with my improved drain, showing the drain in horizontal section on the line 1—1 of Figure 2.

Figure 2 is a vertical sectional view of said drain, taken on the line 2—2 of Figure 1; and

Figure 3 is a diagrammatic view, illustrating in transverse cross-section, the tank, the floating roof, and the drain which removes rain or snow water from the top side of the roof.

In Figure 3 of the drawing, A designates a tank that is used to store gasoline or oil, and B designates a floating roof that is adapted to cover and be supported by the gasoline or oil x in said tank. 5 My invention consists of a double inverted siphon drain that is used to carry off rain water or snow water from the top side of the roof B and discharge said water downwardly into the oil x in the tank A. Said drain comprises a receptacle or 10 tub C carried by the roof B and arranged so that water which falls on or collects on the roof can flow or drain into the open upper end of said receptacle, a tubular outlet or discharge pipe D at the lower end of the receptacle C through which 15 water escapes from said receptacle and flows downwardly into the body of oil x on which the roof floats, and a sealing member or baffle E removably mounted in the receptacle C and accessible from the top side of the roof, the lower 20 end portion of said baffle E being submerged in a liquid sealing medium y in the receptacle C.

As shown in Figures 1 and 2, the receptacle C, which is tub-shaped in general form or outline, tapers inwardly from its upper to its lower end, 25 and is rectangular-shaped in horizontal cross section, said receptacle being provided at its upper end with a laterally-projecting flange 1 that is attached to the roof B in concentric relationship with a drain hole 2 in said roof. The outlet or 30 discharge pipe D of the drain is formed by an open-ended, vertically-disposed, tubular member that is rigidly attached to the bottom 3 of the receptacle C, the upper end of said discharge pipe terminating some distance above the bottom 3 of 35 said receptacle. The sealing member or baffle E is removably mounted in the receptacle C, and is arranged between the inlet at the upper end of said receptacle and the discharge pipe or outlet D of the drain. Said baffle or sealing member E 40 conforms approximately to the shape of the side wall 4 of the receptacle C, and is so proportioned with relation to said receptacle, that when said baffle E is in its operative position, shown in Figure 2, there is a tall, relatively narrow slot or 45 space between the side wall 4 of the receptacle C and the side wall portion of said baffle. The open lower end of the baffle E is maintained in spaced relationship with the bottom 3 of the receptacle C by any suitable means, such, for example, as by legs 5 at the lower end of the side wall portion of the baffle E. When my improved drain is designed for use on a floating tank roof, it is not necessary that the upper end of the tubular baffle or sealing member E be closed, but 55 in order to reduce evaporation losses, I prefer to

arrange a removable cover or closure F in the upper end portion of the baffle E. The removable closure F, shown in Figure 2, preferably has a sliding fit with the upper end portion of the sealing member E and is made of relatively great length or depth, so as to minimize evaporation losses.

Before the tank is filled with oil, gasoline or other liquid, a liquid sealing medium y, preferably water, is introduced into the receptacle C, so as to fill the lower end portion of said receptacle up to the top edge or upper end of the outlet or discharge pipe D of the drain. Thereafter, the baffle or sealing member E is introduced into the receptacle C, so as to form a baffle between the discharge pipe D and the inlet at the upper end of the receptacle C. After sufficient oil has been introduced into the tank to cause the roof B to start to float, oil will flow upwardly through the discharge pipe D of the drain and fill the upper portion of the sealing member E above the level of the liquid sealing medium y, thereby depressing or lowering the level of the column of sealing water in the space between the discharge pipe D and the side wall portion of the baffle E, and raising or increasing the level of the column of sealing water in the space between the side wall portion of the baffle E and the side wall 4 of the receptacle C. By the time sufficient oil has been introduced into the tank to float the roof B, or cause said roof to be entirely supported by the oil in the tank A, the column formed by the sealing water balances the lighter specific gravity oil, and the liquid sealing medium y remains in substantially the position shown in Figure 2, wherein the heavy horizontal lines y designate the liquid sealing medium, and the lighter horizontal broken lines designated by the reference character x, represent the oil from the tank that has backed up into the baffle E through the discharge pipe D and which floats on the liquid sealing medium y that previously was introduced into the receptacle C. At the first rain, the rain water escapes from the top side of the roof and enters the space or slot between the side wall 4 of the receptacle C and the side wall portion of the baffle E, thereby causing the sealing water y in the space between the discharge pipe D and the side wall portion of said baffle to rise, with the result that some of the water overflows the top edge of the discharge pipe D and escapes downwardly through same into the body of oil on which the roof floats. The area of the space between the discharge pipe D and the side wall portion of the baffle E is preferably made three or four times the area of the narrow slot between the side wall 4 of the receptacle C, and the side wall portion of the baffle E, so that one inch of evaporation (say, during a long dry spell) from the water surface in said narrow slot, will usually be only one-third to one-fourth of the replenishing supply of water in the space between the discharge pipe D and the side wall portion of the baffle E.

One of the main advantages of my improved drain is that it permits water to be used as the liquid sealing medium of the drain, because the thin column of water in the tall, narrow, tubular space between the baffle and the side wall 4 of the receptacle C and the shallow puddle of water in the space between the baffle and the discharge pipe D, can freeze solid without danger of breaking or cracking the co-acting parts of the drain. Another desirable feature of the drain, is that

it can be cleaned, inspected, or repaired, in the case of a floating roof, while the roof is floating on the liquid in the tank, and in the case of a breather type roof while the tank is under pressure. All that is necessary in the event inspection, cleaning or repair of the drain becomes necessary, is to close the outlet or discharge pipe D of the drain and then lift the baffle or sealing member E upwardly out of the receptacle C. Various means can be used to close the discharge pipe D when the baffle E is to be removed. One means that can be employed for this purpose, is any suitable kind of a plug that can be inserted in the upper end of the discharge pipe D, after the cover F of the sealing member E has been removed and preparatory to withdrawing the sealing member E from the receptacle C. I prefer, however, to mount a valve or closure G on the upper end portion of the discharge pipe D, and provide means for causing said valve to close automatically when the baffle E is removed, and to open automatically when the baffle E is replaced in the receptacle C. As shown in Figures 1 and 2, a weighted valve or closure G, that is pivotally mounted on the upper end portion of the discharge pipe D, is provided with a laterally-projecting arm 6. An actuating device 7, that is carried by the baffle E, is so arranged that when said baffle is moved downwardly into the receptacle C, the actuating device 7 will engage the arm 6 of the valve G, and move said valve upwardly into its open position, shown in Figure 2. When the baffle E is withdrawn from the receptacle C, the actuating device 7 will be disengaged from the arm 6 of the valve G, and said valve will then drop into its closed position, thus closing the outlet or discharge pipe D of the drain. All of the above described operations can be performed from the top side of the roof B when the roof is floating on the liquid in the tank. When my improved valve is intended to be used on a breather type roof, it is necessary to use a substantially inverted, cup-shaped sealing member or baffle, or, in other words, a sealing member whose upper portion is gas-tight. In Figure 4 of the drawing I have illustrated a drain designed for use with a breather type roof. In general construction, it is similar to the drain shown in Figure 2, except that the removable sealing member or baffle E' is provided with a gas-tight head or upper end F'. The side wall portion of the receptacle C is attached to the roof B, so that its upper end terminates above the top side of the roof, thus causing water to collect on the roof to a depth of several inches before the water starts to flow or drain into the receptacle C. Instead of making the side wall of the receptacle C and the side wall portion of the baffle E' tapered, said parts may be made straight. They can either be of rectangular shape in cross section, or of cylindrical shape.

Having thus described my invention, what I claim as new and desire to secure by Letters Patent is:

1. A siphon drain, comprising a receptacle disposed so that drain water will enter the upper end of said receptacle, the side wall portion of said receptacle sloping outwardly from its lower towards its upper end, a vertically-disposed outlet or discharge pipe for said receptacle having its upper end terminating at a point above the bottom of said receptacle, said receptacle being adapted to contain a liquid sealing medium when the drain is in use, and a baffle of substantially the same shape as the side wall portion of the

receptacle, arranged between the side wall portion and discharge pipe of said receptacle with its lower end submerged in the liquid sealing medium and spaced away from the bottom of said receptacle.

2. A drain of the kind described in claim 1, in which the space between the baffle and the side wall portion of the receptacle constitutes a relatively tall, narrow slot having a width approximately one-third the width of the annular space between the baffle and the discharge pipe of the receptacle.

3. A drain of the kind described in claim 1, in which the discharge pipe is provided with a valve, and means controlled by the baffle for opening and closing said valve.

4. A drain, comprising a receptacle disposed so that water can drain or flow into the upper end of said receptacle, an outlet or discharge pipe

in the bottom of said receptacle, projecting upwardly into same and terminating at a point above the bottom of said receptacle, said receptacle being adapted to contain a liquid sealing medium when the drain is in use, a baffle or sealing member removably mounted in said receptacle between said discharge pipe and the side wall of the receptacle and arranged with its lower end portion submerged in the liquid sealing medium and spaced away from the bottom of said receptacle, and a valve for closing said discharge pipe when the baffle is removed.

5. A drain of the kind described in claim 4, having provision for causing said valve to close automatically when the baffle is removed and for opening said valve automatically when the baffle is replaced in said receptacle.
